ILLUMINATING MEANS FOR FOUNTAINS

Edwin G. Trowbridge, Phoenix, N. Y.

Application July 5, 1938, Serial No. 217,569

7 Claims. (Cl. 299—4)

This invention appertains to fountain structures, and more especially to illuminating means therefore as disclosed in my pending application Serial No. 168,495, filed October 11, 1937, 5 together with improvements therein. Through provision of such illuminating means, novel and highly pleasing ornamental or scenic effects may be obtained, thus enhancing the beauty of the fountain.

10 As disclosed in my earlier application above referred to, the fountain embodies a fountain head which is adapted to be connected to a suitable source of water so that the water may be directed outwardly and downwardly from the head in the form of a substantially unbroken dome-like sheet, and the light rays are preferably directed against the inner surface of the sheet of water, thereby causing the same to flare or glow in an unusual and very attractive manner.

15 The fountain head is preferably of such construction that the same is caused to rotate so that the sheet of water will vary in configuration from time to time. This produces a scintillating effect which contributes to the general 20 beauty of the fountain. It is to be understood, however, that while I prefer to use the illuminating means of the present invention in conjunction with a fountain head of the special construction covered in my aforementioned application,

25 such conjoint use is not essential as the illuminating means may also be used to great advantage with other kinds of fountain heads, including those which produce either jets or sprays of water, or combinations of the same. Moreover, my special fountain head may be employed 30 without any illumination.

The illuminating means to which the present application is primarily directed embodies in general a plurality or series of electric lamps, 40 preferably colored, which are arranged upon a suitable support for selective use in forming different geometrical or figurative designs. One of the primary objects of the invention is to provide a means for conveniently and effectively confining the light rays so that the design will be better defined, and at the same time, I preferably provide a means for concealing the lights so that the design can only be seen from a point above the lights.

To this end, the invention contemplates the provision of a plurality of hollow shells which may be placed over the lights in such manner that the inner surfaces of the shells act as reflectors, and the shells together form the geo-

metrical or figurative designs. By varying the size and shape of the shells, which are preferably open from end to end, an unusually wide range of variation in the illuminated design as a whole may be effected at no, or at the most, 5 very little additional cost.

By reason of the hollow form of the reflecting shells, which are axially open so that the water may freely fall into the same and pass out at the bottom thereof, I obtain the maximum illuminating effect at a minimum expenditure of electrical energy, as will hereinafter more fully appear.

Other objects and advantages of the invention will be hereinafter described and the novel features thereof defined in the appended claims.

In the drawings:

Figure 1 is a view, partly in vertical section and partly in elevation, of an illuminated fountain embodying my invention;

Figure 2 is a fragmentary top plan view illustrating a typical arrangement of the illuminating means to form a distinctive, generally star-shaped pattern or design;

Figure 3 is a fragmentary vertical sectional view illustrating certain improvements in the illuminating means disclosed in my prior application, and having particular regard for the ring-like shields which encircle the lamp support and associated reflecting shells;

Figure 4 is a vertical sectional view taken through one of the lamp sockets and its support, the lamp being shown in elevation;

Figure 5 is a view in side elevation of a removable socket plug;

Figure 6 is a view in top plan of the arrangement shown in Figure 3, illustrating reflecting shells of various sizes and shapes for forming various kinds of designs or patterns;

Figure 7 is a top plan view of the outer ring-like shield and its supporting means;

Figure 8 is a perspective view of a pair of reflecting shells which may be used to make up the whole or a part of the illuminated design, one shell being arranged within the other, the outer shell being generally triangular in horizontal cross-section, and the inner shell being generally circular in horizontal cross section; and

Figure 9 is a view in side elevation of the inner shell shown in Figure 8.

Like reference characters designate corresponding parts in the several figures of the drawings.

Referring first to the general fountain assem-

20

40

45

55

bly in Figure 1, 1 designates a basin or tank forming a pond or pool for receiving the water as it is discharged from the fountain head which is generally designated 2. This head is preferably located substantially centrally of the pond or pool, and may be of special construction, as disclosed in my pending application previously mentioned, or it may be of any other suitable type to produce one or more jets or sprays of water. As shown in the drawings, the basin or tank 1 is constructed of concrete but it is to be understood that a metal or other type of basin may be substituted therefor if desired, in which latter case the entire fountain construction may be preassembled into more or less unitary form prior to installation, if preferred. Disposed at one side of the pond, and preferably housed within a chamber or compartment 3, is a pump 4, having its intake 5 arranged to withdraw water from the pond or pool through a screen or filter 6. The outlet 7 of the pump is connected through means of a conduit 8 to the bottom of the fountain head 2, which is provided at its lower extremity with a threaded coupling 9 or other suitable connection. 10 designates an overflow pipe or outlet conduit, the upper extremity of which is disposed slightly below the upper edge of the basin 1 so that the water in the pond will not exceed a predetermined level. The lower end of the overflow pipe or conduit 10 is connected to a waste line 11, leading to a suitable point of discharge such as a sewer or the like, and if desired, a drain pipe 12, connected at one end to the waste pipe 11 and communicating with the interior of the pump compartment 3 at its other end, may be provided to drain water which may seep into the compartment 3 or otherwise gain access to the compartment, as for example, through pump leakage. It is to be understood that the fountain is not limited to the use of a pump such as described above, since the fountain head 2 may, if preferred, be directly connected to a suitable water supply, such as the usual domestic or city water system. However, for the sake of economy, the water is preferably recirculated through the fountain, in which case, the pump may be availed of to withdraw the water from the pond or pool and force it through the fountain head at the desired pressure and rate of flow. Following discharge from the fountain head, the water is collected in the pond or pool so as to become available for recirculation.

Considering now the illuminating system which constitutes the invention of this application, I provide a base or plate 13 for supporting a plurality of electric lamps 14, preferably of one or more colors. This plate 13 is composed of metal or any other suitable material, and is preferably circular in form and of a size to accommodate a fairly large number of lamps 14, according to the type or types of illuminated designs which are to be created, and the size of the fountain as a whole. As shown in the drawings, the plate is fixedly mounted on the vertical section 8' of the water supply line 8 so as to be positioned slightly above the water line 15 of the pond or pool. Other ways of supporting the plate 13 will readily suggest themselves to those skilled in the art, and it is therefore to be understood that it is not essential that the plate be mounted on the water supply line, or that the fountain head be disposed in the center of the pond. However, in the case where my special fountain head is employed, I preferably make the plate 13 slightly greater in

diameter than the maximum lateral spread of the sheet of water produced by the head, so that the sheet of water will fall principally onto the plate near the marginal edge of the latter when the fountain head is adjusted to the maximum lateral spread of the water. The outer edge of the plate 13 is preferably curved downwardly, as at 16, so that the water which is deposited on the plate can freely run off and fall into the pond or pool.

A plurality of openings 17 is provided in the plate 13 for the reception of lamp sockets 18, which may be of standard construction or otherwise, as desired, the sockets being suitably secured to the plate, as by means of bolts or screws 19, as best seen in Figures 1 and 4. By arranging the lamps 14 in the sockets 18 in various orders, different patterns or designs can be established, and these patterns or designs may be changed from time to time by a rearrangement of the lamps. In order to make the patterns or designs more pronounced, and to obtain a maximum intensity of illumination with a minimum consumption of electrical energy, I preferably provide a plurality of hollow shells which are positioned over the lamps 14 in such manner that the light rays will be reflected against the inner surfaces of the shells and principally confined in an upward direction. One typical arrangement of the shells is shown in Figure 2, wherein each of the shells designated 20 is generally triangular in horizontal cross-section and the group of shells forming a star-shaped pattern. The lower ends of the shells rest upon the base plate 13 with their vertical walls disposed in spaced relation to the lamps 14. The shells are preferably of uniform height, and their upper extremities preferably extend slightly above the lamps 14. In order to prevent water from collecting and remaining within the shells and thus submerging the lamps, the lower extremities of the shells are preferably notched, as indicated at 21 in Figures 1, 2 and 8. These cut away portions of the shells allow the water to freely escape therefrom as it falls into the open upper extremities of the same, and pass outwardly towards the marginal edge of the base plate 13 where it can run off into the pool. Instead of notching or cutting away the lower edges of the shells, as above mentioned, the shells may be spaced slightly above the base plate 13 by any suitable spacing means which will permit the water to freely pass beneath the shells and over the base plate. After assembling the shells to form the particular design desired, they may be secured together by any suitable fastening means so as to prevent inadvertent displacement thereof. In Figures 6 and 8, I have shown a simple form of fastening means, designated 22, comprising a generally U-shaped member of relatively stiff and springy wire or other suitable material which may be forced over the contiguous edges of adjacent shells, thereby clamping the same together, as will be obvious. It is to be understood, however, that I do not wish to be limited to any particular form of fastening means, and in most instances, the fastening means may be omitted since the weight of the shells is ordinarily sufficient to maintain the same in assembled relation after the design has been made up.

Provision is made for sealing the lamps 14 relatively to the sockets 18 to prevent the entrance of water into the sockets and consequently minimize short circuits. As shown in Figure 4, a rubber or other yieldable ring-like gasket 23 is applied to the base of each lamp 14 before it is screwed into its socket, and as the lamp is screwed

into the socket, the gasket will be compressed or clamped between the upper extremity of the socket and the contiguous wall of the glass bulb, as clearly shown in Figure 4.

5 In forming the star-shaped design shown in Figure 2, less than all of the lamp sockets 18 need be availed of. As previously mentioned, however, there is a socket mounted in each opening 17 in the base plate 13 so that changes in the 10 design or pattern of the illuminating means may be quickly made when desired. Those lamps which are not needed to make up the predetermined design may be removed from their sockets and a plug generally designated 24, as shown in 15 Figure 5, may be screwed into each empty socket, thereby excluding the water therefrom. This plug 24 is composed of a threaded body 25 adapted to mate with the threads with which the lamp sockets are provided, and at the upper extremity 20 of the threaded body 25, there is provided an enlarged head 26 which serves as a knob to facilitate the application of the plug to the socket and the removal of the plug when it is desired to substitute the plugs for the lamps, and vice 25 versa. A flexible or yieldable washer or gasket 27 positioned around the threaded body 25 just below the head or knob 26 serves to effectively seal the plug relatively to the socket when the plug is screwed firmly into the same, thereby 30 clamping the gasket 27 between the head 26 and the upper edge of the socket 18, as will be obvious.

The lamps may be arranged in one or more circuits suitably connected to a source of electrical energy. As shown in Figure 1, 28 designates an electrical cable which leads from a source of electrical energy (not shown) to the lamp and pump motor circuits. According to the arrangement illustrated, the lamps are arranged in two separate circuits, each of which is independently controlled by the respective switches 29 and 30. A third switch 31 serves to control the pump motor 32 which is operatively connected with the pump 4 to drive the latter. The circuit arrangement may be varied as desired, and the typical arrangement which is shown in Figure 1 will be readily understood without requiring further description of the same. Obviously, by suitably actuating the switches 29 and 30, the illumination afforded by the lamps may be varied somewhat without any variation of the arrangement of the lamps themselves. On the other hand, further variations of the illumination may be effected by rearranging the lamps in the various sockets provided on the base plate 13, with or without varying the arrangement of the hollow shells 20. The lamp sockets are preferably all connected by a waterproof cable 28' in one or the other of the lamp circuits controlled by the switches 29 and 30, so that no changes in the circuit wiring are required to modify the illuminating effect.

Referring particularly to Figures 6, 8 and 9, several different types of reflecting shells have been shown. In Figure 6, the triangular shells 65 20 hereinbefore referred to are illustrated in an arrangement somewhat different from the star design of Figure 2. The entire design may be made up of these shells 20 as illustrated in the upper portion of the figure and also in broken lines. On the other hand, portions of the design may be formed by shells of one or more other shapes. For instance, 20' designates a shell generally diamond-shaped in horizontal cross-section, and 20'' designates shells of generally leaf-shaped configuration in horizontal

cross-section. In each case, the shells are hollow, which is to say, they are open at their upper extremities, and provision is preferably made at their lower extremities so that the water may pass out of the same and over the base plate 13 5 towards the outer margins of the latter. I have found that such an arrangement constitutes a substantial improvement over illuminating means formerly used in association with fountains and embodying an arrangement of lights which are 10 covered by glass or other transparent or translucent material. In these prior constructions just referred to, the electric lamps are sealed water-tight in one or more compartments, thus trapping air in the compartment. By reason of 15 the difference in temperature within the lamp compartments and outside of the compartments (having in mind that the heat generated by the lamps raises the temperature of the air within the lamp compartments, whereas the water 20 outside of the compartments cools the air), there is a tendency for moisture to condense within the lamp compartments causing the glass or other transparent or translucent cover to become 25 clouded or fogged. This results in a material reduction in the intensity of the illumination which must be suitably compensated for, if at all, by an increase in the candlepower of the electric lamps. My illuminating system completely avoids these objections, and I am able to attain 30 an unusually high efficiency of illumination through employing the open shells hereinbefore described. The inner surfaces of the shells serve as reflecting surfaces, and the water which falls into the shells and flows over the base plate 13 35 forms an additional reflecting surface.

Also in Figures 6, 8 and 9, I have shown a cylindrical shell 20'' which is especially useful in combination with the triangular shells 20. The diameter of the shell 20'' is preferably such that 40 the shell will fit within the triangular shell, as best shown in Figures 6 and 8. The lower extremity of the cylinder is notched or cut away at spaced intervals, as at 21', to allow the water to escape as previously explained. Of course, the shells 20'' may be used alone or in combination with one or more differently shaped shells so that it is possible to make up practically an infinite number of different designs with a very few different types of shells. 45

Referring now to Figures 3, 6 and 7, I have shown a somewhat modified structure wherein one or more shields are employed to improve the appearance of the illuminating means especially 55 in certain types of designs. 32 designates a ring-like shield which extends around the base plate 13 and assembly of lights and reflecting shells carried thereby, the shield being preferably secured to the downwardly turned edge 16 of the base 60 plate 13, as by means of bolts 33 and spacer means 34, the latter being arranged at intervals between the shield 32 and the rim 16 of the base plate. Thus the water flowing over the base plate 13 is allowed to fall over the rim 16 between the rim 65 and the shield 32. The upper edge of the shield 32 is preferably disposed substantially on a level with the upper extremity of the reflecting shells, thus concealing the laterally exposed faces of the reflecting shells and preventing the illuminated 70 design from being seen excepting when viewed from a position somewhat above the level of the lights 14. This shield 32 may be used alone, or in combination with another ring-like shield 35 spaced outwardly from the same, this latter shield 75

being supported by any suitable means such as a spider 36 and vertical standards 37 to which the radial arms of the spider 36 are secured at their outer extremities. The standards 37 may be extended upwardly above the spider and fastened to the shield 35 adjacent to its upper extremity by suitable fastening means such as clamps 38. The lower extremity of the shield 35 may rest upon the radial arms of the spider 36. The upper edge of the shield 35 is preferably rolled over, as at 39, to form a finishing bead, thus improving the appearance. If desired, the shield 35 may be used without the shield 32, especially in cases where provision is made for rotating the base plate 13 which carries the lights and reflecting shells. Since the instrumentalities for imparting rotation to the base plate are not essential to the present invention, they have not been shown in the drawings and will not be described herein.

20 The shields 32 and 35, or either of them, effectively prevent the wind from displacing or disarranging the reflecting shields when the fountain structure is located out of doors, thus making it unnecessary to fasten the reflecting shells to the base plate 13. It is to be understood that the fountain structure is applicable to private as well as public use. By private use, I particularly have reference to lawns, yards, gardens, etc. of private homes, as distinguished from public parks. The simplicity and compactness of form of the fountain, and the relatively low cost of operation of the illuminating means contributes substantially to the utility of the fountain for such private use.

30 While the specific details have been herein shown and described, the invention is not confined thereto, as changes and alterations may be made without departing from the spirit thereof as defined by the appended claims.

Having thus described my invention, what I claim as new and desire to secure by Letters Patent is:

1. The combination with a fountain, including means for discharging a liquid in a generally upward direction so that the same will ultimately fall downwardly under the influence of gravity, of illuminating means comprising a substantially horizontal support, a plurality of electric lamps mounted on said support at spaced intervals, and reflector means associated with said electric lamps for forming a predetermined design or pattern which is visible only from a point above the elevation of the lamps, said reflector means comprising a plurality of hollow shells carried by said support and having substantially vertical walls disposed in spaced relation to the lamps so as to form axially open lamp compartments.
2. Apparatus as defined in claim 1, wherein the lower edges of the reflecting shell are spaced from the lamp support at one or more points so as to permit the liquid which may fall into the upper open ends of the shells to pass out at the lower extremities of the shells and flow over the surface of the lamp support.
3. Apparatus as defined in claim 1, in combination with an annular shield extending about the lamp support and the lamps and reflecting shells carried thereby, said shield being spaced from the outer margin of the lamp support so as to provide a passage therebetween for allowing any liquid which may fall onto the lamp support

to pass off the same at its outer edge, and the upper extremity of the shield being positioned substantially on a level with the upper extremities of the reflecting shells.

4. Apparatus as defined in claim 1, in combination with an annular shield extending about the lamp support and the lamps and reflecting shells carried thereby, said shield being secured to the margin of the lamp support in spaced relation thereto so as to form a passage therebetween for allowing any liquid which may fall onto the lamp support to pass off the same at its outer edge, and the upper extremity of the shield being positioned substantially on a level with the upper extremities of the reflecting shells. 15

5. Apparatus as defined in claim 1, in combination with an annular shield extending about the lamp support and the lamps and reflecting shells carried thereby, said shield being secured to the margin of the lamp support in spaced relation thereto so as to form a passage therebetween for allowing any liquid which may fall onto the lamp support to pass off the same at its outer edge, and the upper extremity of the shield being positioned substantially on a level with the upper extremities of the reflecting shells, and another annular shield surrounding the first mentioned annular shield in spaced relation thereto and supported independently thereof. 20

6. Apparatus as defined in claim 1, in combination with an annular shield extending about the lamp support and the lamps and reflecting shells carried thereby, said shield being secured to the margin of the lamp support in spaced relation thereto so as to form a passage therebetween for allowing any liquid which may fall onto the lamp support to pass off the same at its outer edge, and the upper extremity of the shield being positioned substantially on a level with the upper extremities of the reflecting shells, and another annular shield surrounding the first mentioned annular shield in spaced relation thereto and supported independently thereof. 30

7. In a fountain, a basin, a water supply pipe extending vertically upwardly from said basin,

a fountain head mounted on the upper end of said supply pipe for producing an unbroken substantially dome-shaped sheet of water spreading laterally from the head and downwardly into the basin, and illuminating means mounted within the unbroken portion of the dome-shaped sheet of water above the basin aforesaid so that the light rays will be reflected against the inner side of the sheet and cause the water to flare or glow, said illuminating means including a horizontally disposed support mounted on the vertical supply pipe, a plurality of axially erect electric lamps mounted on said support and arranged at spaced intervals about the supply pipe, and reflector means associated with the electric lamps and arranged to form a pattern or design, said reflector means comprising a plurality of vertically open hollow shells mounted upon the support and surrounding the lamps in spaced relation thereto for permitting ingress and egress of the water in the zone of the lamps. 50

EDWIN G. TROWBRIDGE. 70
